UNITED STATES PATENT OFFICE.

GEORGE WILLIAM STEIN, OF WASHINGTON, DISTRICT OF COLUMBIA.

FLY-TRAP.

No. 866,398.

Specification of Letters Patent.

Patented Sept. 17, 1907.

Application filed April 1, 1907. Serial No. 365,670.

To all whom it may concern:

Be it known that I, GEORGE WILLIAM STEIN, a citizen of the United States, residing at Washington, District of Columbia, have invented a certain new and useful Improvement in Fly-Traps; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to fly traps and has for its object to provide a simple and efficient means for trapping flies which is particularly simple in its construction and cheap and easy to manufacture.

It is well known that flies on the interior of a building congregate in large numbers on the window panes and along the window sash in their endeavor to reach the outside; and I have found by experience that flies can be trapped in very much larger numbers at or near a window in a building than at any other locality. I have therefore designed a simple fly trap which is arranged on the window pane and against the inner edge of the window sash in such manner that the same is scarcely visible or noticeable either from the inside or outside of the window, at the same time this particular location of the trap is arranged directly in the usual path of the flies thereby making it possible to trap a larger number of flies and in a shorter period of time than if the same trap were located on the window or sash.

My invention consists in the novel construction of the fly trap as will be first fully described and afterwards specifically pointed out in the appended claims.

Referring to the accompanying drawing: Figure 1 is a fragmentary view of a portion of a window pane and sash showing two traps in operative position. Fig. 2 is a vertical sectional view through a portion of a window pane and sash taken on line 2—2 of Fig. 1. Fig. 3 is a vertical longitudinal sectional view through one of the cone shaped entrances of the trap. Fig. 4 is a vertical longitudinal sectional view of one of the ends of the trap. Fig. 5 is a vertical transverse sectional view through the trap taken on line 5—5 of Fig. 4. Fig. 6 is an elevation partly in section showing a trap made of paper, and Fig. 7 is a vertical longitudinal sectional view through a portion of the trap showing receptacle holding a poisonous liquid.

Like numerals of reference indicate the same parts throughout the several figures in which;

1 indicates the window pane, 2 the window sash and 3 the trap.

As shown in Fig. 1 the trap may either be rectangular in order to fit snugly against a corner of the window

pane one portion of the trap extending along the vertical portion of the sash and the other portion extending along the horizontal portion of the sash or it may be straight in form in order to fit snugly against the side of the window pane and against the inner edge of the sash, either along the said top or bottom of the sash.

The trap 3 is preferably constructed of a suitable wire screen although it may be made of paper or other suitable material as shown in Fig. 6. In any event it is formed in cross sections substantially as shown in Fig. 5, having a vertical wall 4 which rests against the window pane and a flat bottom 5 which rests against the inner edge of the sash and the curved side 6.

As shown, the ends 7 of the trap are preferably inclined and arranged to receive a cone shaped entrance 8, said cone shaped entrance having a reduced inner end 9 and inwardly extending wires or prongs 10 so as to allow easy entrance of the flies and to prevent ready exit of the flies from the trap. The outer end 11 of the entrance 8 is preferably inclined to conform to the inclined end 7 of the trap, and a small wire or handle 12 is provided in order to allow the entrance 8 to be readily withdrawn manually for the purpose of emptying the trap.

As shown in Fig. 7 whenever the trap is arranged in the bottom edge of the window pane it is sometimes desirable to insert a small receptacle 13 of poisonous liquid or other material therein so that the flies when entering the trap will be killed, thereby rendering the emptying of the trap much easier. If desired a strip of fly paper 15 can be inserted on the bottom of the trap as shown in Figs. 4 and 6.

As shown in Fig. 1 one or more small brads 14 can be utilized for securely holding the trap in position against the edge of the sash.

Having thus fully described my invention what I claim as new and desire to secure by Letters Patent of the United States is:—

1. A fly trap for use along the edge of a window pane having a flattened portion to lie against the window pane and a flattened portion to lie against the window sash, the ends of said trap being inclined, and a removable cone shaped entrance arranged in one of the said inclined ends of the trap, substantially as described.

2. A fly trap formed to fit a corner of a window sash having one portion thereof extending along the vertical part of the sash and fitting snugly thereon, and the other portion of the trap extending along the horizontal portion of the sash and fitting snugly thereon, and a cone shaped entrance for said trap, substantially as described.

In testimony whereof, I affix my signature, in presence of two witnesses.

GEORGE WILLIAM STEIN.
